UNITED STATES PATENT OFFICE

HERBERT THOMAS GIRDLESTONE AND JAMES REST, OF LONDON, ENGLAND

COLLAPSIBLE CONTAINER

Application filed August 18, 1928, Serial No. 299,301, and in Great Britain February 4, 1928.

This invention relates to closures for collapsible containers and has for its object to provide improvements therein.

In accordance with this invention we provide for a container of which the internal volume can be controlled, for example, by a collapsible body, said container being provided with an orifice having a comparatively stiff projection at least partly round said orifice in combination with a closure member adapted to pass through said orifice, said closure member having a conical form spreading outwards below and upwardly terminating in a peak, the neck of the closure member, on closing the container exactly fitting into the opening and closing tightly up to the wall of the opening, whilst at the same time the upper surface of the spreading part of the closure member closes up against the whole inner surface of the stiff projection to form a tight closure and having preferably a slight clearance from the sides whereby the amount of material extended is controlled. The invention also consists in a closure member, substantially as hereinafter described.

The accompanying drawings illustrate one form of device for example a tube, made in accordance with this invention.

Fig. 1 is a sectional elevation of a tube fitted with one closure member.

Fig. 2 is an elevation of the closure member.

Figs. 3, 4, 5 and 6 are sectional elevations of tubes fitted with modified forms of closure members.

Fig. 7 is an elevation of a modified form of closure member.

Fig. 8 is a sectional elevation of a further modification.

Fig. 9 illustrates a further modification in elevation.

Fig. 10 illustrates a form of pin used in Fig. 9.

Fig. 11 illustrates a further modification in elevation.

Fig. 12 is a plan of the modification illustrated in Fig. 11 and

Fig. 13 shows a plan of the top of the container in Fig. 5.

Fig. 14 is an elevation of Fig. 9.

In Figs. 1 and 2 of the drawings a tube *a* of collapsible material is provided at one end with a comparatively stiff shoulder *b* partially closing that end of the tube but leaving a central orifice *c*. A closure member to said orifice is provided consisting of a stopper *c'* of substantially hollow bell shape, the flange of the bell being considerably turned outwards to form a shoulder *d* adapted to coact with the shoulder *b* on the container, the body part *e* of the bell being of a suitable size to fill the orifice *c* in the container when the shoulders of container and closure member are in contact, there being a slight clearance between the sides *f* of the tube and the shoulder *d* of the closure member which regulates the amount of material extruded, for example paste and paints. The tube is adapted to be filled through its open end *g* with contents *h* for example, paste.

In use the closure member is first inserted in the tube *a* through the open end and the protuberant or body part *e* of the closure member is passed through the orifice at the other end of the tube so that the shoulders *b*, *d* on the container and the closure member are in contact. The tube is then filled with material and sealed at the open end *g* by the usual method. The protuberant part *e* of the closure member may now be pressed down or backwards through the orifice and will allow some of the contents of the tube to rise above the shoulder *d* on the said closure member. If now the collapsible tube *a* is pinched the contents *h* that are on top of the shoulder of the closure member will be extruded through the orifice action of the closure member. The hollow interior of the bell shape of the closure member assists in the centering thereof. The downward or opening movement of the closure member may be limited by a shoulder.

In Fig. 3 the shoulder *d'* of the stopper *c'* is smaller than that shown in Fig. 2 so that a greater clearance is given between it and the wall of the container, thereby a smaller quantity being extruded.

In Fig. 4 the top of the stopper *c'* is shown having a central part *k* shouldered to allow of its retaining some of the contents of the tube which can be wiped off.

In Fig. 5 the shouldered part k is shown as disposed at the side of the stopper c' . In Fig. 13 there is a passage q' for stopper c' .

In Fig. 6 the part k' is shown as hinged to the stopper c' as at m so that it can be folded down for better wiping, also to prevent the closure being accidentally pushed back.

In the form illustrated in Figs. 7 and 8 the stopper is slightly shouldered or indented as at o to allow of the shoulder on the container engaging therewith and disengaging owing to its resilience when the stopper is pressed downwards. This prevents the stopper being pushed back accidentally.

15 A resilient cover p to the stopper device may be provided with any of the above forms to keep said device clean. The cover p engages with a recess in the container neck.

20 In the forms illustrated in Figs. 7 and 8, the closure member is preferably formed of a hollow stamping or moulding of a suitable material, cone shaped and having a straight shoulder at o .

25 In the form illustrated in Figs. 9 and 14, a hollow groove r is provided at the closure member c' outside the nozzle, into which a spring U-shaped clip n , as illustrated in Fig. 10 may be disposed to prevent the nozzle or closure member slipping back into the container by accident at undesirable times. The 30 spring slip n is inserted in the groove r around the closure when the groove is in such a position that it is in alignment with the top of the shoulder or projection of the tube. It is then impossible for the closure to be forced back.

35 When the tube is first filled for transport, the spring wire clip n is inserted in the groove r , thus ensuring that the closure cannot be knocked back. After the tube has been 40 opened the spring clip may then be dispensed with.

45 Figs. 11 and 12 illustrate a further manner of locking the enclosure. In this form a projection p' is provided on the closure member and is adapted to slide through a groove q in the container top. The projection p' is shouldered at its under end so that the projection leaves the groove q when the closure member is at the outer end. The projection p' engages with a ledge or annular projection s on the top of the orifice of the container and prevents the closure member slipping back.

55 In use owing to the large area of contact between the closure nozzle and the shoulder of the container tube the air tightness of the closure is ensured.

60 The quantity exuded is governed by the diameter of the flange d of the container and the length of the conical or body part e . The larger the diameter of the flange and the longer the conical part, the greater the amount exuded, as only the contents of the tube which are pushed on the top of the flange

d by the action of pushing the closure into the tube are extruded by the action of squeezing the tube which ejects this predetermined quantity and at the same time closes the tube air tight.

70 As there are no springs or other similar mechanical devices inside or outside the closure, and as the surfaces are rounded and without projections, the closure member is always wiper perfectly clean and no deposits of the 75 contents are left exposed to the air to be contaminated thus ensuring a truly hygienic device. By no chance can the contents of the tube be exposed to the air.

When the closure member closes fully to 80 close the orifice of the tube, the groove r is disposed at such a height thereon that this shoulder s allows of the insertion of the spring clip n in said groove.

85 In the modification illustrated in Figs. 11 and 12, rotation of the projection p' out of register with the groove q has a similar effect of preventing the closure member being forced back, by said projection p' engaging with the projection s of the tube.

90 The closure is an air tight one.

95 The details of the invention may be varied without departing from the scope thereof.

What we claim and desire to secure by Letters Patent is:

1. A container of which the internal volume can be controlled, for example, by a collapsible body, said container being provided with an orifice having a comparatively stiff projection at least partly round said orifice in combination with a closure member adapted to pass through said orifice, said closure member having a conical form spreading outwards below and upwardly terminating in a peak, the neck of the closure member, on closing the container exactly fitting into the opening and closing tightly up to the wall of the opening, whilst at the same time the upper surface of the spreading part of the closure member closes up against the whole inner surface of the stiff projection to form a tight closure.

100 2. A container according to claim 1 having a slight clearance between the sides of the container and the spreading part of the closure member.

105 3. A container in combination with a closure member according to claim 1 and releasable means for preventing the closure member being forced back into the container when such action is not desired.

110 In testimony whereof, we affix our signatures.
